United States Patent Office

Des. 211,936
Patented Aug. 13, 1968

211,936

BAIL PULL OR THE LIKE

Lionel C. Algoren, Evanston, Ill., assignor to National Lock Co., Rockford, Ill., a corporation of Delaware

Filed Dec. 14, 1967, Ser. No. 9,787

Term of patent 14 years

(Cl. D10—8)

FIG. 1.

FIG. 2

FIG. 3

FIG. 4

FIG. 2 is a side elevational view thereof;

FIG. 3 is a rear elevational view thereof;

FIG. 4 is a cross sectional view thereof taken on the line 4—4 of FIG. 1; and

FIG. 5 is a top plan view thereof.

I claim:

The ornamental design for a bail pull or the like, substantially as shown.
